SELF-PINNING CLOTHESLINE

Joaquim S. Jardim, Newark, N. J.

Application October 24, 1951, Serial No. 252,903

8 Claims. (Cl. 211—119.02)

1

This invention relates to a self-pinning clothesline.

More specifically, the present invention proposes the construction of an improved clothesline which when stretched between two clothes poles or other supports can be used to hang articles of clothing to dry and/or air without having to use any clothespins or other fasteners for securing the articles of clothing to the line.

Another object of the present invention proposes constructing the self-pinning clothesline to have a central nonstretchable core enclosed in an elastic covering having spaced portions of semicircular cross-section engaged about the core in a manner to have the portions of semicircular cross-section lifted away from the core so that the corners of the articles of clothing can be inserted between the core and the portions of semicircular cross-section to be frictionally gripped thereby when the portions of semicircular cross-section are again released.

A further object of the present invention proposes constructing the elastic covering to have portions of circular cross-section between the portions of semicircular cross-section which portions of circular cross-section have an inside diameter to frictionally grip the core in a manner to retain the covering against longitudinal movement relative to the core.

Still another object of the present invention proposes forming the portions of semicircular cross-section with means whereby a finger grip can be conveniently had thereon to facilitate lifting the portions of semicircular cross-section away from the core so that the corners of the articles of clothing can be inserted therebeneath.

It is a further object of the present invention to construct self-pinning clotheslines which are simple and durable, which are effective for their intended purposes and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a view of a portion of a clothesline constructed in accordance with the present invention in use supporting an article.

Fig. 2 is an enlarged detailed view of a portion of Fig. 1.

Fig. 3 is an enlarged sectional view taken on the line 3—3 of Fig. 2.

2

Fig. 4 is an enlarged sectional view taken on the line 4—4 of Fig. 2.

Fig. 5 is a view similar to a portion of Fig. 1, but illustrating the clothesline constructed in accordance with a modification of the present invention.

Fig. 6 is a vertical sectional view taken on the line 6—6 of Fig. 5.

Fig. 7 is an enlarged detailed view of a portion 10 of the clothesline shown in Figs. 5 and 6.

Fig. 8 is an enlarged sectional view taken on the line 8—8 of Fig. 7.

Fig. 9 is a view similar to Fig. 2, but illustrating another modification of the present invention.

Fig. 10 is an enlarged sectional view taken on the line 10—10 of Fig. 9.

The self-pinning clothesline, according to the first form of the present invention shown in Figs. 1 to 4, includes a non-stretchable core 10. The core 10 is made of any desired material such as metal or a synthetic resinous material, but is preferably a conventional clothesline of cotton, hemp or similar fabric materials.

The entire length of the core 10 is enclosed 25 within an elastic covering 11 formed of any desired elastic material, but preferably made of rubber, either natural or synthetic. The elastic covering 11 is characterized by the fact that it has portions of semicircular cross-section 11a which are spaced from one another by portions of circular cross-section 11b. The portions of semicircular cross-section 11a extend about the top of the core 10 and the circular portions 11b completely surround the core 10. The portions of circular cross-section 11b have an internal diameter to frictionally grip the core 10 and maintain the covering 11 against movement longitudinally along the length of the core.

When in use, the clothesline has its ends 40 passed about pulleys 12 engaged with hooks 13 or the like mounted on the top ends of clothespoles 14 or the like. Adjacent ends, not shown, of the clothesline are knotted together so that the line will be continuous to move between the pulleys 12 when pulled in one direction or the other.

An article of clothing or the like 15, which is illustrated on Figs. 1 and 2 as being a towel or the like, is secured to the line without using any clothespins or other fasteners. Attachment is accomplished by pulling the portions of semicircular cross-section 11a away from the core 10 so that the corners of the article of clothing 15 can be inserted between the core 10 and the portions of semicircular cross-section 11a.

The portions of semicircular cross-section 11a are then released so that the inserted corners

will be gripped between the core 10 and the portions of semicircular cross-section 11^a. The roundness of the portions of semicircular cross-section 11^a and the core 10 cooperate to securely hold the inserted corners and prevent disengagement of the article of clothing from the line.

The modification of the invention shown in Figs. 5 and 8 is characterized by the provision of a means whereby a grip can be had on the portions of semicircular cross-section 11^a to facilitate their being lifted away from the core 10 to have the corners of the article of clothing 15 inserted therebeneath.

The grip means is comprised of short tabs 16 which are integrally formed with the covering 11. There is one tab 16 for each of the portions of semicircular cross-section 11^a and those tabs are projected radially upward from the top faces of the portions of semicircular cross-section 11^a.

The pulleys 12', see Figs. 5 and 6, used for supporting the modified clothesline are provided at the inner edges of the grooves around which the clothesline runs with an inwardly extended slot 12^a for accommodating the tabs 16 when the tabs carrying portions of semicircular cross section 11^a of the covering 11 pass about the pulleys.

In all other respects, the form of the invention shown in Figs. 5 to 8 is similar to that described in connection with Figs. 1 to 4 and like numerals of reference are used to identify like parts.

The modification of the invention shown in Figs. 9 and 10 which is similar to that shown in Figs. 5 to 8, is characterized by a different means for facilitating gripping the portions of semicircular cross-section 11^a.

In that further modification, the gripping means is characterized by small semicircular loops 17. There is one semicircular loop 17 for each of the portions of semicircular cross-section 11^a of the covering 11 and those semicircular loops are all integrally formed with the covering 11.

The modified clothesline of Figs. 9 and 10 must be used with pulleys of the type described in connection with Figs. 5 to 8 in order to provide clearance for the semicircular loops 17.

Portions of the modification of the invention shown in Figs. 9 and 10 which correspond to portions of the previous forms of the invention shown in Figs. 1 to 4 and Figs. 5 to 8 are designated by the same reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A self-pinning clothesline comprising an endless non-stretchable core, and an elastic concentric, tubular covering enclosing said core for its entire length, said covering having elongated portions of circular cross-section separated by elongated portions of semicircular cross-section, so constructed and arranged that said portions of semicircular cross-section can be lifted away from said core to have articles of clothing inserted therebetween to be frictionally gripped between said core and said portions of semicircular cross-section.

2. A self-pinning clothesline comprising a non-stretchable core, and an elastic covering enclosing said core, said covering having elongated portions of circular cross-section separated

said core, said covering having elongated portions of circular cross-section separated by elongated portions of semicircular cross-section, so constructed and arranged that said portions of semicircular cross section can be lifted away from said core to have articles of clothing inserted therebetween to be frictionally gripped between said core and said portions of semicircular cross-section, said core being of fabric construction.

3. A self-pinning clothesline comprising an endless non-stretchable core, and an elastic concentric, tubular covering enclosing said core for its entire length, said covering having elongated portions of circular cross-section separated by elongated portions of semicircular cross-section, so constructed and arranged that said portions of semicircular cross-section can be lifted away from said core to have articles of clothing inserted therebetween to be frictionally gripped between said core and said portions of semicircular cross-section, said covering being made of rubber.

4. A self-pinning clothesline comprising an endless non-stretchable core, and an elastic concentric, tubular covering enclosing said core for its entire length, said covering having elongated portions of circular cross-section separated by elongated portions of semicircular cross-section, so constructed and arranged that said portions of semicircular cross-section can be lifted away from said core to have articles of clothing inserted therebetween to be frictionally gripped between said core and said portions of semicircular cross-section, said circular portions having an internal diameter to frictionally grip said core and hold said covering against sliding relative to said core.

5. A self-pinning clothesline comprising an endless non-stretchable core, and an elastic concentric, tubular covering enclosing said core for its entire length, said covering having elongated portions of circular cross-section separated by elongated portions of semicircular cross-section, so constructed and arranged that said portions of semicircular cross-section can be lifted away from said core to have articles of clothing inserted therebetween to be frictionally gripped between said core and said portions of semicircular cross section, and means integral with the portions of semicircular cross-section for facilitating gripping said portions of semicircular cross-section when lifting the same away from said core.

6. A self-pinning clothesline comprising an endless non-stretchable core, and an elastic concentric, tubular covering enclosing said core for its entire length, said covering having elongated portions of circular cross-section separated by elongated portions of semicircular cross-section, so constructed and arranged that said portions of semicircular cross-section can be lifted away from said core to have articles of clothing inserted therebetween to be frictionally gripped between said core and said portions of semicircular cross-section, and means for facilitating gripping said portions of semicircular cross-section when lifting the same away from said core, said gripping means comprising a tab for each of said portions of semicircular cross-section extended upward therefrom intermediate the ends thereof.

7. A self-pinning clothesline comprising a non-stretchable core, and an elastic covering enclosing said core, said covering having elongated portions of circular cross-section separated

by elongated portions of semicircular cross-section, so constructed and arranged that said portions of semicircular cross-section can be lifted away from said core to have articles of clothing inserted therebetween to be frictionally gripped between said core and said portions of semicircular cross-section, and means for facilitating gripping said portions of semicircular cross-section when lifting the same away from said core, said gripping means comprising a semicircular 10 loop for each of said portions of semicircular cross-section extended upward therefrom intermediate the ends thereof.

8. A self-pinning clothesline comprising a non-stretchable core, and an elastic covering 15 enclosing said core, said covering having elongated portions of circular cross-section separated by elongated portions of semicircular cross-section, so constructed and arranged that said por-

tions of semicircular cross-section can be lifted away from said core to have articles of clothing inserted therebetween to be frictionally gripped between said core and said portions of semicircular cross-section, said portions of semicircular cross-section being of uninterrupted uniform thickness from end to end.
